(57) **CLAIM**

The ornamental design for a portable charger, as shown and described.

DESCRIPTION

FIG. 1.1 is a perspective view of a portable charger showing my new design;

FIG. 1.2 is another perspective view thereof;

FIG. 1.3 is a top view thereof;

FIG. 1.4 is a back view thereof;

FIG. 1.5 is a left view thereof;

FIG. 1.6 is a right view thereof; and

FIG. 1.7 is an exploded view thereof.

The front view and bottom view are omitted because they are the mirror image of the back view and top view, respectively.

The broken lines in the drawings depict portions of the portable charger that form no part of the claimed design.
